UNITED STATES PATENT OFFICE.

WILLIAM MITCHELL, OF ALTOONA, PENNSYLVANIA.

DESIGN FOR A WASHBOILER-SCREEN.

SPECIFICATION forming part of Design No. 22,923, dated November 28, 1893.

Application filed October 12, 1893. Serial No. 487,994. Term of patent 7 years.

To all whom it may concern:

Be it known that I, WILLIAM MITCHELL, a citizen of the United States, residing at Altoona, in the county of Blair and State of Pennsylvania, have invented a new and original Design for Washboiler-Screens, of which the following is a specification.

The invention relates to a new and original design for wash boiler screens.

10 The object of the present invention is to provide an attractive screen; and the essential feature resides in a frame having parallel bars and curved ends, and rectangular loops arranged at intervals and disposed transversely and provided with centrally arranged cylindrical posts.

15 In the drawings—Figure 1 is a perspective view of a wash boiler screen showing my new and original design. Fig. 2 is an end view of the same.

20 Referring to the drawings, 1 designates a

frame having parallel bars 2 and 3, and provided with transverse loops 4, which are arranged at intervals at right angles to the bars. The bars 2 are arranged at the sides of 25 the frame, and the bar 3 is arranged midway between the bars 2, and the frame is provided with curved ends 5 presenting convex outer edges. The transverse loops 4 are rectangular or oblong, and each one is provided with 30 a central cylindrical post.

What I claim is—

The design for a wash boiler screen herein shown and described.

In testimony that I claim the foregoing as 35 my own I have hereto affixed my signature in the presence of two witnesses.

WILLIAM MITCHELL.
